QUATERNARY AMMONIUM COMPOUNDS

Joseph Emmett Carpenter, Greenwich, Conn., assignor to American Cyanamid Company, New York, N. Y., a corporation of Maine

No Drawing. Application August 28, 1953,
Serial No. 377,247

4 Claims. (Cl. 260—97.5)

This invention relates to novel quaternary ammonium compounds and to a process of preparing the same.

The novel quaternary ammonium compounds may be represented by the following general formula:

wherein R_1 represents a hydrocarbon radical of a fatty acid containing at least 8 carbon atoms, R_2 represents a hydrocarbon radical of a rosin acid, R_3 and R_4 are members of the group consisting of methyl and ethyl radicals, n is an integer having the values of 2 to 10, inclusive, and X is a member of the group consisting of chlorine, bromine and iodine.

The new compounds are surface active agents and are highly useful as cationic flotation agents, textile assistants, emulsifying agents, detergents, asphalt additives, as well as being useful in the preparation of bentonite greases.

The products of the present invention are prepared by a two-stage reaction, in the first of which a fatty acid is reacted with an asymmetric dialkyldiamine of the formula:

at a temperature of from about 120° C. to 300° C. with the elimination of water to produce the amide condensate of the formula:

in which n , R_1 , R_3 and R_4 have the significance noted above.

In the second stage, this fatty amide condensate is reacted with a rosin acid and an epihalohydrin. The epoxy ring of the epihalohydrin opens and forms an ester linkage with the rosin acid, while simultaneously the halide reacts to form a quaternary ammonium salt with the tertiary amine group in the fatty amide, condensate. The reaction in the second stage is exothermic and takes place spontaneously at an initial temperature of about 50–75° C., the temperature thereafter rising, usually to a little over 100° C. It is advisable, however, in order to insure completion of this reaction, to hold the reaction mixture at about 100° C. for several hours, or at higher temperatures for shorter periods of time. Temperatures up to about 200° C. can be used, although danger of discoloration and decomposition begins at about this point.

A variety of higher fatty acids or derivatives may be employed for reaction with the dialkyldiamine. The carbon chain length in the fatty acid is preferably from 8 to 30 carbon atoms, and the hydrocarbon chain may be saturated or unsaturated. Representative higher fatty acids that may be used are lauric, palmitic, stearic, oleic, ricinoleic, capric, myristic and mixtures of such acids. The esters of these acids, particularly the esters from methanol, ethanol, glycol and glycerol can be advantageously used instead of the free acids. In such cases, the respective alcohols will be liberated in the first-stage reaction with the diamine and will be removed from the reaction mixture or not depending on their volatility. Consequently, mixtures of fatty acids and their glycerides

such as those found in naturally occurring animal, vegetable and marine oils such as coconut oil, palm oil, cottonseed oil, linseed oil, soya bean oil, olive oil, peanut oil, fish oils, and fractions from the refining of these oils may be advantageously used.

The rosin acids which may be used in the present process include abietic acid and its isomers, including hydrogenated and disproportionated types as well as the naturally occurring varieties, such as gum and wood rosin.

10 In a preferred embodiment of the present invention, I prefer to use tall oil as the source of both the fatty acids and the rosin acids. As is known, tall oil, as produced as a by-product from sulfate paper manufacture, is composed of a mixture of rosin acids, fatty acids (principally oleic acid and linoleic acid), lignin and unsaponifiable matter. Crude tall oil generally contains a relatively large proportion of rosin acids, frequently as much as 50% rosin acids. Depending upon the extent of purification, it is possible to obtain various purified fractions of tall oil where the rosin content may run as low as 10%. When tall oil is to be used as the source material of both fatty acids and rosin acids, I may use any grade of tall oil, that is, crude, distilled or hydrogenated, provided that in those cases in which the mol per cent of rosin acids exceeds that of the fatty acids, it will usually be advantageous to provide enough additional fatty acid so that the proportion of fatty acid in the initial reaction mixture is equal to or exceeds that of the rosin acids.

When tall oil is used as a source of fatty acids as well

30 as rosin acids, it is apparent that opportunity will be provided in the first stage of the reaction for the rosin acids as well as the fatty acids to react with the primary amino group of the diamine. It might be supposed that some rosin acids will be consumed in this reaction so that the

35 composition of the final product will differ from that hereinbefore described. I have found, however, that such is not the case because the rosin acids are very much less reactive toward amines than are the fatty acids and, therefore, the latter will be consumed first. Moreover, in the

40 usual and preferred practice of this invention, the quantity of dialkyldiamine employed in the first step of the reaction is chemically equivalent to the quantity of fatty acids in the reaction mixture and, consequently, no difficulty is encountered in reacting substantially all of the fatty

45 acids while leaving substantially all of the rosin acids unreacted in the first step.

It is an important advantage of this invention that, when employing tall oil as the starting material, the rosin acids of the tall oil are completely reacted in the final

50 product. In most reactions employing tall oil, the rosin acids react very sluggishly, and much less completely than would be expected from the corresponding reactions employing abietic acid and most commercial forms of rosin.

The most plausible explanation appears to be

55 that the rosin acids of tall oil are isomers of abietic acid which have been formed in the heat treatment during the wood cooking process, and which are relatively inert.

However, by the use of an epihalohydrin, which is a very reactive chemical, to combine with the fatty amide condensate and with the rosin acids of tall oil in the second stage of reaction, it has been found that complete reaction of the rosin acids takes place very easily.

It is another advantage of this invention that the ester linkage, once it has been formed by reaction of the rosin

60 acids with the epihalohydrin, displays the same inertness and stability characteristics of the original rosin acids.

For this reason, hydrolysis of the ester linkage does not occur readily, and in applications where resistance to

65 hydrolysis is of importance, the products of the present

70 invention are about equally as stable as cationic surface active agents obtained from fatty acids and employing only amide linkages.

Among the epihalohydrins which can be utilized to

75 form the quaternary ammonium compounds of the present invention are epichlorohydrin, epibromohydrin, epiiodohydrin.

The products of this invention are also very suitable starting materials for the preparation of a large class of surface active agents in which the hydroxy group formed

80 by the opening of the epoxy ring is reacted with other epoxy compounds, particularly ethylene oxide and propyl-

ene oxide, to produce products of modified properties. The invention will be described in greater detail in conjunction with the following specific examples in which the parts are by weight unless otherwise specified.

Example 1

313.0 parts (1 eq.) of crude tall oil, (Saponification No. 179.3, Acid No. 166.0, Rosin Acid No. 89.4, corresponding to a content of 0.499 equivalent of rosin acids) and 54.0 parts (0.529 mol) of 3-dimethylaminopropylamine were mixed and heated in a flask equipped with a fractionating column leading to a distillation condenser. Distillation began at a pot temperature of 165° C., and the reaction was stopped after 30 minutes at a pot temperature of 207° C., at which point distillation of water was complete. Potentiometric titration of a sample of the amide intermediate with standard alcoholic HCl showed a basic amine content of 0.546 equivalent, nearly all of which was dimethylamino nitrogen with only a very minor amount of primary amino nitrogen. Potentiometric titration of another sample with standard KOH in methanol showed a free carboxylic acid content of 0.512 equivalent. 50.0 parts (0.530 eq.) of epichlorohydrin were added to the amide intermediate at 56° C., a spontaneous reaction taking the temperature to 127° C. in 8 minutes, but without causing refluxing of epichlorohydrin. The mixture was then heated at 154–160° C. for 1 hour, and on cooling produced a dark, sticky solid which dispersed in hot water, making a foamy solution.

The fatty and rosin acids of hydrogenated tall oil show the same difference in reactivity toward 3-dimethylaminopropylamine as those of ordinary tall oil. Hydrogenated tall oil can be substituted for ordinary tall oil with equal success.

Example 2

289.6 parts (1 eq.) of distilled tall oil (Saponification No. 193.7, Acid No. 188.0, Rosin Acid No. 55.0, corresponding to a content of 0.284 equivalent of rosin acids), and 73.0 parts (0.716 mol) of 3-dimethylaminopropylamine were reacted as in Example 1. The distillation began at 175° C. and the reaction was completed after 45 minutes at a final pot temperature of 250° C. The intermediate amide product was found by potentiometric titration to contain 0.696 eq. of basic amino nitrogen and 0.342 eq. of uncombined carboxylic acids. 33.8 parts (0.356 eq.) of epichlorohydrin and 44.1 parts (0.340 eq.) of technical benzyl chloride were added in separate steps with cooling in between. The mixture was thereafter held at 135–147° C. for 1 hour to insure completion of the reaction. The final product was a reddish solid on cooling, and dispersed in hot water giving a foamy solution.

This example illustrates a situation very common in practice in cases where the proportion of rosin acids in the tall oil employed is less than that of the fatty acids. Instead of adding more rosin acid, the proportion of epichlorohydrin can be adjusted to the quantity of unreacted rosin acids present after the initial reaction, and there results a mixture consisting of the product of this example together with the surplus fatty amide condensate. While in some cases it is satisfactory to leave the surplus fatty amide condensate as it is, it will generally be

preferred to convert it also to a quaternary ammonium salt, by reaction with benzyl chloride as shown, or with additional epichlorohydrin or with any of the various other quaternizing agents known to the art. The order of addition of the epichlorohydrin and the other quaternizing agents is ordinarily immaterial, and they may also be added simultaneously.

Example 3

10 214.7 parts (1 eq.) of coconut oil (Saponification No. 261.3) and 116.2 parts (1 mol) of 2-diethylaminoethylamine are heated together under reflux until refluxing has ceased to take place, the final temperature being in excess of 230° C. The 3-acylamidoethylidethylamine so produced is cooled and 302.0 parts (1 mol) of abietic acid are added, together with 134 parts tertiary butyl alcohol to serve as a solvent. After the abietic acid has been dissolved by warming and again cooling to about 50° C., 137.0 parts (1 mol) of epibromohydrin is added, and following the temperature rise from spontaneous reaction, the mixture is heated to the reflux temperature of the tertiary butyl alcohol for several hours. The final product has properties similar to the products of Examples 1 and 2.

25 I claim:

1. The process of preparing a quaternary ammonium compound of the following general formula:

wherein R₁ represents a hydrocarbon radical of a fatty acid containing at least 8 carbon atoms, R₂ represents a hydrocarbon radical of a rosin acid, R₃ and R₄ are members of the group consisting of methyl and ethyl radicals, n is an integer having the values of 2 to 10, inclusive, and X is a member of the group consisting of chlorine, bromine and iodine, which comprises reacting a dialkylamine of the formula:

50 with a fatty acid at a temperature of from about 120° C. to 300° C. and then reacting the amide condensate so formed with a rosin acid and an epichlorohydrin at a temperature not appreciably greater than 200° C.

2. The process according to claim 1 in which the fatty acid and rosin acid are derived from tall oil.

3. The process according to claim 2 in which the dialkylamine is 3-dimethylaminopropylamine.

4. The process according to claim 2 in which the epichlorohydrin is epichlorohydrin.
